DESIGN FOR A CHILD'S HANDBAG

Moe J. Cohen and Abraham Wirklich,
New York, N. Y.

Application March 31, 1939, Serial No. 83,940

Term of patent 3½ years

To all whom it may concern:

Be it known that we, Moe J. Cohen and Abraham Wirklich, citizens of the United States of America, residing in New York city, in the Borough of Manhattan, county and State of New York, have invented a new, original, and ornamental Design for a Child's Handbag, of which the following is a specification, reference being had to the accompanying drawing, forming part thereof, wherein,

We claim:

The ornamental design for a child's handbag, substantially as shown.

MOE J. COHEN.
ABRAHAM WIRKLICH.
